US00D993970S

(12) **United States Design Patent** (10) **Patent No.:** **US D993,970 S**
Scavo (45) **Date of Patent:** **** Aug. 1, 2023**

(54) **DISPLAY SCREEN OR PORTION THEREOF WITH GRAPHICAL USER INTERFACE FOR A WATCHLIST**

(71) Applicant: **Nowcasting.ai, Inc.**, Palo Alto, CA (US)

(72) Inventor: **Damian Ariel Scavo**, Palo Alto, CA (US)

(73) Assignee: **Nowcasting.ai, Inc.**, Palo Alto, CA (US)

(**) Term: **15 Years**

(21) Appl. No.: **29/805,017**

(22) Filed: **Aug. 24, 2021**

(51) LOC (14) Cl. **14-04**

(52) U.S. Cl.

(57) **CLAIM**

The design for a display screen or portion thereof with graphical user interface for a watchlist, as shown and described.

DESCRIPTION

The FIGURE illustrates a front view of a display screen or portion thereof with a graphical user interface for a watchlist.

The broken lines in the drawing illustrate portions of the article or environment that form no part of the claimed design.

1 Claim, 1 Drawing Sheet
